UNITED STATES PATENT OFFICE.

JAMES L. ROBERTS, OF PONTIAC, ILLINOIS.

CAR-LOADER.

SPECIFICATION forming part of Letters Patent No. 655,831, dated August 14, 1900.

Application filed April 24, 1900. Serial No. 14,156. (No model.)

To all whom it may concern:

Be it known that I, JAMES L. ROBERTS, a citizen of the United States, residing at Pontiac, in the county of Livingston and State of Illinois, have invented a new and useful Car-Loader, of which the following is a specification.

My invention is an improved car-loader, the object of my invention being to provide novel means for loading grain-cars, vessels, and the like from elevators, whereby the grain may be simultaneously and uniformly thrown to opposite ends of the car or hold of the vessel and uniformly distributed therein.

My invention consists in the peculiar construction and combination of devices herein-after fully set forth, and pointed out in the claims.

In the accompanying drawings, Figure 1 is a side elevation of a car-loader constructed in accordance with my invention, showing the same arranged in operative position in a car. Fig. 2 is a vertical longitudinal sectional view of the same. Fig. 3 is a vertical transverse sectional view of the same looking from the interior of the car. Fig. 4 is partly a top plan view and partly a longitudinal horizontal sectional view of the same.

The supporting-frame 1 of my improved car-loader is rectangular in form and comprises the sills 2, the ends of which are connected by the transverse beams 3. A longitudinally-inclined chute 4 is supported above the frame 1 and thereon by suitable standards 5. The rear upper end of said chute is open, as at 6, and the lower front or inner end of the chute discharges onto a pair of revolute shovels 7. The said shovels are provided with radial blades or paddles 8 and disks 9 at the ends thereof, which connect said radial blades or paddles and in connection therewith form longitudinally-disposed cups 10 in the revolute shovels. The latter are supported on shafts 11, which have their bearings in the standards 5, as shown, and said shafts are provided at their rear ends with beveled pinions 12, which are fast thereon. The said beveled pinions are engaged by beveled gear-wheels 13, which are fast on a shaft 14, that is transversely disposed on

the frame 1 and journaled in suitable bearings 15.

It will be understood from the foregoing and by reference to the drawings that by rotating the shaft 14 the revolute shovels 7 may be caused to rotate simultaneously in opposite directions, as indicated by the arrows in Fig. 3. Power may be communicated to the shaft 14 from any suitable engine or source of power by any suitable means, such as an endless belt and pulleys, and for illustrative purposes I have shown the said shaft 14 as provided with such pulleys, whereby it may be rotated.

The shafts 11 are disposed in nearly-horizontal planes, the planes of said shafts converging with the planes represented by the bottom of the inclined chute 4, and the revolute shovels are correspondingly shaped, the same being smaller at their outer ends than at their inner ends.

A case comprising an inner wall 16 and an outer wall 17 is disposed transversely at the discharge end of the chute 4 and above the revolute shovels. The central portions of 75 said walls are connected together by deflectors 18, the same being disposed above the oppositely-revolute shovels and in a vertical plane midway between them. Said deflectors are provided with hinged or otherwise movable and adjustable extensions 19, which are adapted to be adjusted toward or from the revolute shovels, so as to widen or narrow the space above them and to alter the "throw" of the revolute shovels, and suitable means 85 are provided for securing said adjustable deflectors 19 in position when properly set. I have here shown the adjustable deflectors 19 as hinged to the deflectors 18, as at 20, and I have also shown adjusting-rods 21, which are 90 adapted to be inserted in appropriate adjusting-openings 22, with which the walls 16 17 are provided, and to engage keepers 23 on said adjustable deflectors 19, and hence said rods 21 are adapted to secure said adjustable 95 deflectors when the latter are set. It will be understood, however, that other suitable means may be provided for supporting and adjusting the deflectors, and thereby regulating the throw of the revolute shovels by 100

2
changing the radius of the curves described by the grain thrown by the revolute shovels, as will be readily understood.

In operation the inner end of my car-loader 5 is inserted in a grain-car through one side thereof, the outer end of the loader being supported in any suitable manner, as by a trestle or horse, such as is illustrated at A in Fig. 1. Grain being delivered onto the inclined 10 chute 4 from an elevator or other source and power being applied to the revolute shovels, so that the latter are rotated, as before described, the grain is caused to flow downward on the inclined chute 4, to be discharged from 15 the latter onto the oppositely-rotating shovels and caught and thrown by the latter to the ends of the car and evenly distributed therein, the throw of the shovels being regulated by means of the adjustable deflectors, as hereinbefore described. Any desired number of 20 the radial shovels may be provided on each shaft as may be required.

Having thus described my invention, I claim—

25 1. In a car-loader of the class described, the combination of a pair of oppositely-revolute shovels arranged side by side, a chute to deliver grain onto the opposing sides of the

said oppositely-revolute shovels, and the oppositely-extending deflectors disposed above 30 the said shovels, substantially as described.

2. In a car-loader of the class described, the combination of a pair of oppositely-revolute shovels arranged side by side, a chute to deliver grain onto the opposing sides of the 35 said oppositely-revolute shovels and the oppositely-extending deflectors disposed above the said shovels, said deflectors having adjustable extensions, substantially as described.

3. In a car-loader of the class described, 40 the combination of a pair of oppositely-revolute shovels, arranged side by side and having their axes converging toward their outer ends, the opposing sides of said shovels being parallel, a chute to deliver grain onto said opposing sides of said shovels, and deflectors disposed above said shovels, substantially as described.

In testimony that I claim the foregoing as my own I have hereto affixed my signature in 45 the presence of two witnesses.

JAMES L. ROBERTS.
